The ornamental design for a circular pan, as shown and described.

DESCRIPTION

FIG. 1 is a top side perspective view of a circular pan in accordance with the invention shown;

FIG. 2 is a left side view of the circular pan from FIG. 1;

FIG. 3 is a right side view of the circular pan from FIG. 1;

FIG. 4 is a front side view of the circular pan from FIG. 1;

FIG. 5 is a back side view of the circular pan from FIG. 1;

FIG. 6 is a top plan view of the circular pan from FIG. 1; and,

FIG. 7 is a bottom plan view of the circular pan from FIG. 1.
